UNITED STATES PATENT OFFICE.

WILLIAM PORTER MASON, OF NORFOLK, VIRGINIA.

HAND DUPLICATOR.

Application filed October 2, 1924. Serial No. 741,229.

To all whom it may concern:

Be it known that I, WILLIAM P. MASON, a citizen of the United States, residing at Norfolk, in the county of Norfolk and State 5 of Virginia, have invented a new and useful Hand Duplicator, of which the following is a specification.

This invention relates to an improved hand duplicator of the type which comprises 10 a stencil frame with an inking device therein, and provided with means for receiving and holding a stencil sheet on which any desired description may be cut.

The general object of the present invention is to provide a device of this type which 15 may be economically manufactured, which operates with the greatest accuracy and efficiency, and in which the assembly of the various parts, and the securement of the 20 stencil sheet thereto may be accomplished in the most effective and expeditious manner.

The present invention is of the same general type as that disclosed in an earlier application, Serial No. 712,322, filed May 10, 25 1924, but embodies certain improvements thereover. The specific structure of these improvements and their advantages will be more fully explained in the following detailed description taken in connection with 30 the accompanying drawings, which illustrate the invention in its preferred form.

In the drawings:

Figure 1 is a perspective view of the invention.

Figure 2 is a plan view thereof, with certain parts broken away or shown in section.

Figure 3 is a vertical transverse section.

Figure 4 is a perspective view of the main 40 frame or holder detached.

Figure 5 is a perspective view of the stencil frame detached.

Figure 6 is a perspective view of the inking pad.

Figure 7 is a bottom plan view of a portion of the device.

In the form herein shown, the invention includes a main frame or holder, preferably 50 rectangular in shape, having vertical side walls 10 and 11, connected by end walls 12. A flange or ledge 13 extends inwardly from the bottom of the side and end walls, defining a rectangular opening, through which projects the diaphragm 14. The latter is 55 curved downwardly, and is formed with vertical sides 15 with their upper portions bent

upon themselves, as shown in Figure 3, and terminating in laterally disposed flanges 16, which are transversely curved or corrugated to fit over similarly shaped corrugations or 60 channels 17, formed in the side flanges 13 of the main frame.

The ink holder, as shown in Figure 6, comprises an inner layer of felt 18 and an outer facing of fine cotton cloth 19 or the like, 65 and a pad 20 therebetween, the several layers being bound together by parallel rows of stitching 21, leaving a certain amount of slack in the outer layers, so that the holder may be stretched over the convexly curved 70 surface of the diaphragm 14 without wrinkling. The diaphragm is provided with numerous perforations 22, through which the ink may be uniformly distributed to the holder. In attaching the ink holder, it is 75 stretched across the under surface of the diaphragm 14, with its side edges clamped between the flanges 13 and 16, and extending between the outer edges of the flanges 16 and the side walls 10 and 11, and being 80 rigidly held thereby.

The front wall 10 is somewhat higher than the rear wall 11, and is formed at its ends with notches 23, which receive the inwardly bent flanges 24 formed on the upper 85 sides of the end walls 12, thus providing a guideway beneath said flanges and above the upper edges of the rear wall 11 and the diaphragm wall 15, for snugly receiving the top plate or cover 25.

The front wall 10 is formed near each end with an upwardly projecting lug 26, with similar lugs 27 spaced from opposite sides thereof, and adapted to receive a spring latch 28 secured to the upper side of the 95 cover 25. Each of these spring latches 28 projects beyond the front edge of the cover plate 25, and is formed with an eye 29 for receiving the lug 26, the front end of the latch being bent upwardly with its corners 100 rounded, so as to be automatically guided into locking position as the cover is slid into place. In order to remove the cover, the ends of the latches 28 must be positively and forcibly lifted to release them from the lugs 105 26. Keepers 30 are preferably formed on the front edge of the cover plate to prevent the latches 28 from being lifted beyond their elastic limit.

The rear wall 11 of the main frame is 110 formed with a plurality of rectangular notches 31, which are traversed by strips 32

forming hinge pins about which the stencil frame is adapted to swing. This stencil frame, as shown in Figures 1 and 5, is of the same general shape as the main frame, having a peripheral upstanding flange 33, which fits around the main frame, and formed on its rear side with lugs 34, which, when the device is assembled, are adapted to be bent about the hinge pins 32 to form a hinged connection between the stencil frame and main frame. The stencil frame also has an inwardly disposed flange 35 adapted to fit underneath the flange 18, and provided with upwardly curved corrugations or channels 36 adapted to register with the corresponding corrugations or channels 17. The front side of the stencil frame is provided with upstanding spring latches 37, having inwardly turned lips 38 adapted to engage over the upper edge of the front wall 10 to lock the stencil frame in closed position. Each of these latches 37 is preferably provided with a corrugation 39 in order to stiffen the same, but the latches and the sides of the stencil frame are sufficiently yieldable to permit the latter to be unlatched and opened for the purpose of changing the stencil, which is normally clamped between the side flanges 35 of the stencil frame and the side flanges 13 of the main frame. It is preferred to secure rubber strips 40 to the under sides of the flanges 13, so that the stencil may be more securely held.

It will be observed that the diaphragm is downwardly curved and projects through the main frame and stencil frame, so that it may be rolled over the surface to be printed by means of a suitable handle 41, which is secured to the cover 25. The diaphragm is so designed that its side and end walls meet and rest firmly against the top and sides of the main frame, forming a solid foundation to receive the printing pressure without bending or otherwise injuring the diaphragm. In attaching the ink holder, it is drawn over the surface of the diaphragm, and its edges are drawn over the edges of the flanges 16 which clamp the same against the walls 10 and 11 of the main frame, and as the diaphragm is forced downwardly in the main frame, the side portions of the ink holder are drawn in and clamped between the corrugations or channels, which serve to draw the pad more tightly against the diaphragm, as well as to clamp it more firmly.

The corrugations serve, therefore, not only to clamp the inking pad more firmly in position but to stretch it tightly upon the diaphragm. They also serve to align or center the several parts, and to properly lock them in working position.

The stencil sheet also is drawn tightly over the inking pad by means of the corrugations as the stencil frame is closed, and held in working position by the spring

catches 37. The rubber strips 40 also provide yielding surfaces against which the sides of the stencil sheet are securely held against slipping.

The outer facing of the ink holder is of a quality suitable to properly filter or strain the ink, and also eliminates the grinding of the felt into the stencil sheet, thus rendering it capable of producing cleaner work than where the felt or naked pad comes in contact with the stencil sheet.

The stencil frame is constructed to fit closely within the main frame on all sides, and it is hinged so as to permit of easy opening in order to insert the stencil sheet into printing position. When in position for printing, the stencil frame is held tightly closed by means of the locking springs 37, while the cover plate 25 is firmly held in position between the flanges 24 and the upper edges of the walls 15, and is secured against removal by means of the spring latches 28. The cover plate by engaging the vertical sides (Fig. 3), holds the diaphragm down with the flanges 16 in firm engagement with the ledge 13 of the main frame.

While it is preferred to use the spring latches herein described for securing the cover plate 25 within the main frame, it is quite obvious that other means may be used similar to that disclosed in my earlier application above referred to. It will also be apparent that the various other features of the invention are capable of being modified in various respects without departing from the spirit of the invention. It is my intention, therefore, to include all such modifications within the scope of the appended claims.

What is claimed is:

1. In a hand duplicator, the combination of a main frame having side and end walls and a flange projecting inwardly therefrom and defining an opening through the bottom of said frame, a diaphragm provided with a flange arranged to fit within said walls and rest with its flange upon said inwardly projecting flange, said diaphragm having a downwardly projecting curved surface projecting through said opening, an inking pad, unitary means for securing the diaphragm and pad to the main frame with the pad about the curved surface of said diaphragm, and means for securing a stencil frame and stencil sheet to the main frame in position for stamping.

2. In a hand duplicator, the combination of a main frame having side and end walls defining an opening through the bottom of said frame, a diaphragm having a downwardly projecting curved surface projecting through said opening, an inking pad disposed about the curved surface of said diaphragm, interfitting flanges on the frame

and said diaphragm to engage said pad, a stencil frame carrying a stencil sheet, and means for securing the stencil frame to the main frame.

5. In a hand duplicator, the combination of a main frame having side and end walls defining an opening through the bottom of said frame, a diaphragm having a downwardly projecting curved surface projecting through said opening, an inking pad disposed about said curved surface, means for securing said diaphragm and inking pad in position, a stencil frame carrying a stencil sheet, and means for securing the stencil frame to the main frame.
10. In a hand duplicator, the combination of a main frame having side and end walls defining an opening through the bottom of said frame, a diaphragm having a downwardly projecting curved surface projecting through said opening, an inking pad disposed about said curved surface, means for securing said diaphragm and inking pad in position, a stencil frame carrying a stencil sheet, and means for securing the stencil frame to the main frame.

15. In a hand duplicator, the combination of a main frame having a ledge, a diaphragm fitting within the frame and engaging the ledge, an inking pad adapted to be stretched underneath the diaphragm and also engaging the ledge, a cover slidably engageable with the diaphragm and slidably in the main frame to clamp the diaphragm and pad onto the ledge of said frame, a handle secured to the cover, and means for securing a stencil frame and stencil sheet to the main frame in position for stamping.

20. In a hand duplicator, the combination of a main frame having a ledge transversely corrugated, a diaphragm fitting within the frame and having a flange engaging the ledge and also transversely corrugated, an inking pad adapted to be stretched underneath the diaphragm and engaging the ledge, means for securing the diaphragm and pad to the frame and to hold the flange of the diaphragm in engagement with the ledge with the pad held on the ledge by the flange, a stencil frame carrying a stencil sheet, and means for securing the stencil frame to the main frame in position for stamping.

25. In a hand duplicator, the combination of a main frame having side and end walls and a flange projecting inwardly therefrom and defining an opening through the bottom of said frame, a diaphragm provided with a flange arranged to fit within said walls and rest upon the inwardly projecting flange, said diaphragm having a downwardly curved surface projecting through said opening, and means for clamping the diaphragm in position and simultaneously securing an inking pad therebeneath.

30. In a hand duplicator, the combination of a main frame having side and end walls and a flange projecting inwardly therefrom and defining an opening through the bottom of said frame, a diaphragm provided with a flange arranged to fit within said walls and rest upon the inwardly projecting flange, said diaphragm having a downwardly curved surface projecting through said opening and adapted to receive an inking pad, said end walls being extended upwardly and bent inwardly to form guideways, and a

cover slidable in said guideways, said diaphragm having upwardly projecting portions engageable by the cover to clamp the diaphragm and inking pad in position.

35. In a hand duplicator, the combination of a main frame, a diaphragm fitting within the main frame and having a curved operating surface, an inking pad adapted to be stretched over the curved operating surface and clamped between the diaphragm and main frame, a stencil frame hinged to the main frame and having a peripheral upwardly flange engaging about the same, a stencil carried by the stencil frame and held about the pad, and locking means on the stencil frame engaging the main frame to hold the stencil in place.

40. In a hand duplicator, the combination of a main frame, a diaphragm fitting within the frame, an inking pad adapted to be stretched underneath the diaphragm, and held in the main frame by the diaphragm, said main frame having inwardly turned flanges overhanging the diaphragm and forming guideways, a cover slidable in said guideways and engageable with the diaphragm to clamp said diaphragm and inking pad to the main frame, means for locking the cover in clamping position, and means for securing a stencil frame and stencil sheet in position for stamping.

45. In a hand duplicator, the combination of a main frame, a diaphragm fitting within the frame, an inking pad adapted to be stretched across the diaphragm and clamped between the sides of the latter and the main frame, said main frame having inwardly turned flanges overhanging the diaphragm, a cover slidable beneath said flanges and held thereby in position to clamp the diaphragm and pad to the main frame, means including a spring latch for automatically locking the cover in its clamping position, a handle secured to the cover, a stencil frame hinged to the main frame, and means for locking the stencil frame and simultaneously securing a stencil sheet underneath the surface of the pad.

50. In a hand duplicator, the combination of a main frame having side and end walls and a flange projecting inwardly therefrom, a diaphragm provided with a peripheral flange arranged to fit within said walls, an inking pad adapted to be stretched beneath the diaphragm with its edge portions engaged between said peripheral flange and the side walls, and means to secure the diaphragm and main frame together with their side flanges in clamping relation, said side flanges having registering corrugations which crimp the inking pad and stretch the same across the under surface of the diaphragm.

55. In a hand duplicator, the combination of a main frame having side and end walls and a flange projecting inwardly therefrom, a diaphragm provided with a peripheral flange arranged to fit within said walls, an inking pad adapted to be stretched beneath the diaphragm with its edge portions engaged between said peripheral flange and the side walls, and means to secure the diaphragm and main frame together with their side flanges in clamping relation, said side flanges having registering corrugations which crimp the inking pad and stretch the same across the under surface of the diaphragm.

a diaphragm provided with a peripheral flange arranged to fit within said walls, an inking pad adapted to be stretched beneath the diaphragm with its edge portions engaged between said peripheral flange and the side walls, means to secure the diaphragm and main frame together with their side flanges in clamping relation, said side flanges having registering corrugations 10 which crimp the inking pad and stretch the same across the under surface of the diaphragm, a stencil frame having similar corrugations, and means for securing the stencil frame with its corrugations and corrugations of the diaphragm flanges in clamping relation to a stencil sheet stretched across the pad.

13. In a hand duplicator, the combination of a main frame, a diaphragm and an inking pad carried thereby, a stencil frame having a flange with a surface mating with

a corresponding surface of the main frame, means for bringing the two surfaces together to clamp a stencil sheet stretched across the pad, and an insert or facing of 25 yieldable material, such as rubber, felt or the like, secured to one of the surfaces to yieldably hold the sheet against slipping.

14. In a hand duplicator, the combination of a main frame, a diaphragm, and an inking pad carried thereby, comprising a felt backing, a finely woven facing, and a pad therebetween, the three layers being stitched together by parallel rows of stitching with a certain amount of slack in the outer two 30 layers so that the holder may be stretched across an outwardly bowed surface of the diaphragm without forming any wrinkles.

In testimony that I claim the foregoing as my own I have hereto affixed my signature. 35

WILLIAM PORTER MASON.
